BY
George A. Melvin
ATTORNEY.

UNITED STATES PATENT OFFICE.

WILLIAM A. HUELDONK, OF MODESTO, CALIFORNIA.

CONCENTRATOR.

1,244,611.

Specification of Letters Patent. Patented Oct. 30, 1917.

Application filed September 18, 1916. Serial No. 120,620.

To all whom it may concern:

Be it known that I, WILLIAM A. HUELDONK, a citizen of the United States, residing at Modesto, in the county of Stanislaus, 5 State of California, have invented certain new and useful Improvements in Concentrators; and I do declare the following to be a full, clear, and exact description of the same, reference being had to the accompanying drawings, and to the characters of reference marked thereon, which form a part of this application.

This invention relates to improvements in concentrating apparatus especially adapted 15 for use in connection with placer mining, the object of the invention being to produce in combination with a concentrating table of specific construction a feed trough or hopper therefor which will properly feed 20 and distribute the sand and gravel upon the table to produce the most efficient results.

A further object of the invention is to produce certain coöperating mechanism 25 whereby the concentrator will be continuously vibrated so as to settle the precious metals and allow the lighter nonprecious material to be readily carried off. I aim also to produce a concentrator which can be 30 operated with a minimum amount of water and one in which only the finer sand and gravel containing the precious metals will be ultimately passed to the distributor.

A further object of the invention is to 35 produce a simple and inexpensive device and yet one which will be exceedingly effective for the purposes for which it is designed.

These objects I accomplish by means of 40 such structure and relative arrangement of parts as will fully appear by a perusal of the following specification and claims.

In the drawings similar characters of reference indicate corresponding parts in the several views.

45 Figure 1 is a side elevation of the complete device.

Fig. 2 is a top plan view of the concentrating table.

Fig. 3 is a sectional view on a line X—X 50 of Fig. 1.

Fig. 4 is a sectional view on a line Y—Y of Fig. 2.

Fig. 5 is a view of the discharging end 55 of the concentrating table.

Referring now more particularly to the characters of reference on the drawings, the numeral 1 designates the supporting

frame. At one end thereof is a spindle 2 mounted on which is a supporting frame 3 carrying the separating screen 4. The vibrating rod 5 is connected with the frame 3 at one end and with the lever 6 at the other end. The other end of the lever 6 is provided with a crank arm 7 movable in a guide 8 and being provided with a roller 9 arranged to be engaged by a cam 10. The cam 10 is on the shaft 11 which is arranged to be rotated by means of a pulley 12 connected by a belt 13 with a pulley 14 operated by a suitable motor 15. A spring 16 60 normally holds the frame 3 in that position which will cause the vibrating rod 5 to hold the lever 6 so that the roller 9 will be constantly in the path of the cam 10. Thus with the rotation of the cam 10, the frame 3 and consequently the screen 4 will be constantly vibrated so as to shake the material therein to separate the fine material from the coarse as is common in this class 65 of screen. While the material is being 70 passed through the screen 4, it is continually wetted from the spray pipe 17 fed from the pump 18 connected with any suitable source of supply and operated by and in connection with the power motor 15 as is 75 clearly shown in Fig. 1. The finer sand, gravel and precious metals, together with the water passing through the screen 4, are delivered into the distributor which is disposed longitudinally above the concentrat- 80 85 90

ing table. It is secured to the central bead- 95 ing 19 on the concentrating table 20 by means of the beam 21. Secured to the upper side of the beam 21 is a distributing plate 22 extended longitudinally along the 100 said beam 21 and secured to this distributing plate 22 is a trough-like distributor 23 which receives the material from the screen 4. This distributing trough 23 is provided with a plurality of openings 24 along its 105 lower edge, those openings nearest the screen 4 being somewhat higher than the balance so that the lighter material will be first discharged on to the concentrating table 20. The openings 24 are regulated by slid- 110 able plates 25 so as to control the amount of flow of the material therethrough. As the material flows through the holes 24, it first strikes deflecting plates 26 which discharge upon the distributing plate 22 which dis- 115 tributing plate in turn discharges upon the distributing plates 27, which, as noted, are spaced slightly from the plate 22 and curve downwardly to discharge against the center

of the concentrating table 20 on each side of the central beading 19.

The concentrating table 20 is especially constructed in the following manner, 5 namely: At its receiving end the lowest points of its surface are adjacent the beading 19 and its surface then slopes upwardly on both sides of the said beading to the outer edges where there are small retaining rims 10 28. This condition continues to points as at "a" where the lowest points of the surface deflect outwardly toward the discharging end of the table 20 to points as at "b", the sides thereof sloping upwardly on both 15 sides from the lines "c" so as to form a substantial gully or ditch terminating into a discharging chute 29 at the end of the table 20 for carrying off the high grade precious metals and into side chutes 30 for carrying 20 off the lower grades. The concentrating table 20 is kept in a constant vibratory motion by means of the cam 10 directing against a roller 31 on the thrust end 32 movable through a guide 33 and connected 25 by a rod 34 with the under side of the table 20 near one end thereof as at 35. The said table is mounted on ball and socket supports 36 to allow of this vibratory motion and the roller is held in constant engagement 30 with the cam 10 by means of springs 37.

From the foregoing description it will readily appear that I have produced a distributor and concentrator in which, after the coarse rock is screened from the light sand 35 and gravel, the latter will be carried by the water spray directly into the distributor, which distributor, by reason of its construction, will distribute the material equally all along the concentrating table, the lighter 40 material passing out first toward the upper end of the table. Upon being distributed upon the table, the precious material such as gold, platinum or the like, being heavy will tend to settle into the lower portions 45 "d" adjacent the beading 19 as described, while the lighter material will flow up the inclined surface and wash over the edges of the table, the retaining rims 28 preventing any overflow of the precious metals. The 50 vibration of the table combining with the flow of the water will cause the precious metals to travel along the length of the table until the point "a" is reached, where they will be diverged along the line "c" and thence off into the chute 29. The better 55 grade of material being the heavier will naturally follow the ditch "c" and pass through onto and out through the chute 29 while the lighter or less valuable materials 60 will pass through the outlet slots 30^a and thence onto the chutes 30 and be carried off through said chutes.

By means of my improved concentrating table acting in the manner above described, the action thereof will be very similar to 65 that of the commonly used washing pan which effectually washes off the lighter non-valuable material and washes the valuable materials onto the crevices where they can be held and controlled and eventually 70 handled as found desirable.

From the foregoing description it will be readily seen that I have produced such a device as substantially fulfills the objects of the invention as set forth herein. 75

While this specification sets forth in detail the present and preferred construction of the device, still in practice such deviations from such detail may be resorted to as do not form a departure from the spirit of the 80 invention, as defined by the appended claims.

Having thus described my invention what I claim as new and useful and desire to secure by Letters Patent is:

1. The combination with a concentrating table, of a distributing trough arranged along the length of the table and having a plurality of openings, a distributing plate disposed immediately between the distributor and the concentrating table, deflecting plates between the openings and said distributing plate for directing the material from the distributor upon said distributing plate, and curved distributing plates spaced on each side of the first named distributing 95 plate to discharge on said table.

2. A concentrating table having a beading, the side of the table sloping upwardly from the beading to the opposite edge of the table for a portion of the length of the 100 table so as to form a gully along the beading, such gully then deflecting obliquely from the beading to discharge at the end of the table near the outer edge thereof, the sides of the latter portion of the gully sloping upwardly to the beading and opposite edge of the table respectively. 105

3. A concentrating table having a beading, the side of the table sloping upwardly from the beading to the opposite edge of the 110 table for a portion of the length of the table so as to form a gully along the beading, such gully then deflecting obliquely from the beading to discharge at the end of the table near the outer edge thereof, the 115 sides of the latter portion of the gully sloping upwardly to the beading and opposite edge of the table respectively, the table being provided with an outlet slot opening through the edge of the table into the one 120 side of the obliquely extending portion of the gully.

In testimony whereof I affix my signature.

WILLIAM A. HUELSDONK.
